(57) **CLAIM**

The ornamental design for a audio speaker, as shown and described.

DESCRIPTION

FIG. 1 is a perspective view of a audio speaker showing our new design according to a first embodiment;
FIG. 2 is a front elevational view of the first embodiment;
FIG. 3 is a rear elevational view of the first embodiment;
FIG. 4 is a right side elevational view of the first embodiment;
FIG. 5 is a left side elevational view of the first embodiment;
FIG. 6 is a top plan view of the first embodiment;
FIG. 7 is a bottom plan view of the first embodiment;
FIG. 8 is a perspective view of a audio speaker showing our new design according to a second embodiment;
FIG. 9 is a front elevational view of the second embodiment;
FIG. 10 is a rear elevational view of the second embodiment;
FIG. 11 is a right side elevational view of the second embodiment;
FIG. 12 is a left side elevational view of the second embodiment;
FIG. 13 is a top plan view of the second embodiment;
FIG. 14 is a bottom plan view of the second embodiment;
FIG. 15 is a perspective view of a audio speaker showing our new design according to a third embodiment;
FIG. 16 is a front elevational view of the third embodiment;
FIG. 17 is a rear elevational view of the third embodiment;
FIG. 18 is a right side elevational view of the third embodiment;
FIG. 19 is a left side elevational view of the third embodiment;
FIG. 20 is a top plan view of the third embodiment; and,
FIG. 21 is a bottom plan view of the third embodiment.
The stippling shown in FIGS. 1, 2, 6, 8, 9, 13, 15 and 16 illustrate small circular openings.
The broken lines in FIGS. 1-21 form no part of the claimed design.

1 Claim, 18 Drawing Sheets
